UNITED STATES PATENT OFFICE.

JOHN HAYS HAMMOND, JR., OF GLOUCESTER, MASSACHUSETTS.

POSITION-REVEALING SYSTEM.

Application filed April 4, 1919, Serial No. 287,653. Renewed April 13, 1922. Serial No. 552,132.

To all whom it may concern:

Be it known that I, JOHN HAYS HAMMOND, Jr., a citizen of the United States, and a resident of Gloucester, county of Essex, and State of Massachusetts, and whose post-office address is Hammond Radio Research Laboratory, Gloucester, Massachusetts, have invented certain new and useful Improvements in Position-Revealing Systems, of which the following is a specification.

Some of the objects of the present invention are to provide means to produce and discharge smoke from a torpedo or other submerged body to indicate the position of such body; to provide means for controlling the discharge of smoke from a torpedo; to provide means for revealing the position and course of a submerged body; to provide means to produce smoke upon a submerged body and to control the discharge of the smoke at will from a distance, whereby the position of the submerged body is indicated to an observer; and to provide other improvements as will hereinafter appear.

In the accompanying drawings, Fig. 1 represents a fragmentary sectional elevation of a torpedo, showing one form of the invention; Fig. 2 represents a section on line 2—2 of Fig. 1; Fig. 3 is a view similar to Fig. 1 showing another form of the invention; and Fig. 4 is a view similar to Fig. 1 showing another form of the invention.

Referring to the drawings, one form of the present invention is shown as applied to a torpedo body 10, having an exhaust pipe 11 and being generally of any suitable construction.

For the purpose of confining a suitable smoke producing mixture upon the torpedo body 10, a firebox 12, formed of suitable material, is fixedly mounted within the body 10 and normally contains a supply of pitch 13 or other smoke producing material, which when ignited will give off a dense volume of smoke. This smoke is utilized as a direction indicating means whereby the position and the course of the torpedo 10 may be determined at will as desired.

In order to ignite the smoke producing mixture 13 when the torpedo 10 is fired, or a desired interval thereafter, the firebox 12 is provided with an opening 14 arranged to receive a percussion fuse 15, which may be fired by any suitable mechanism. As here shown a firing pin 16 is employed for this

purpose, the same being mounted for sliding movement in bearings 17 formed respectively in standards 18, which are suitably spaced and so arranged as to support the firing pin 16 in alignment with the percussion fuse 15. Normally the firing pin 16 is held retracted by a trigger 20 arranged, in operative position, to engage a collar 21, which is fixed to the pin 16 and forms an abutment for one end of a coiled spring 22, the other end of which seats against one of the fixed standards 18. In the engaging position of the trigger 20, the spring 22 is compressed and the firing pin 16 is held away from the percussion fuse 15, but in position to strike the fuse 15 when released by the withdrawal of the trigger 20.

For the purpose of releasing the firing pin 16, the trigger 20 is, preferably, formed as a continuation of a piston rod 23, which carries a piston 24 arranged for reciprocating movement in a cylinder 25 supported in any fixed member, such as by an extension 26 of one of the standards 18. A spring 27 is arranged within the cylinder 25 to maintain the piston 24 outwardly pressed to hold the trigger 20 in its lock engaging position. The end of the cylinder 25 on the opposite side of the piston 24 from the spring 27 is in communication with a supply pipe 30 for pressure fluid and the construction is such that the admission of pressure fluid to the cylinder 25 causes the piston 24 to travel inward against the spring pressure and thereby remove the trigger 20 from the path of the collar 21 to release the firing pin 16. In the preferred arrangement the pipe 30 is connected to the air line within the torpedo body and establishes communication between the source of pressure and the cylinder 25 automatically by the opening of a suitable control valve which releases the air when the torpedo is fired. Thus as soon as the air pressure is admitted to the cylinder 25, the piston 24 is moved in a direction to release the trigger 20 and thus allow the pin 16 to fire the percussion fuse 15 to cause the ignition of the smoke producing mixture.

In order to conduct the smoke from the firebox 12 to the exterior of the body 10, it is preferred to employ the exhaust pipe 11 and to that end a tube 32 is provided forming a normally open passage 33 between the pipe 11 and the firebox 12, through which the produced smoke passes to the exhaust and finally rises to the surface of the

water to the rear of the torpedo where it is visible.

To control the discharge of smoke a valve 34, preferably of the butterfly type, is mounted in the passage 33, being fixedly secured to a rotatable spindle 35, which is journaled in and projects from the tube 32 and has its extended end supported in a bearing 36 of a standard 37. This spindle 35 has a ratchet 40 fixedly secured to it in position to be engaged by a spring-pressed pawl 41 pivoted to a gear 42, which is free to rotate with respect to the spindle 35. The ratchet 40 is preferably a four-toothed one in order to transmit a quarter turn to the spindle 35 for each actuation of the gear 42.

For turning the gear 42 so that the valve 34 is either opened or closed, a rack 43 is provided in mesh with the gear 42 and formed on the projecting end of a piston rod 44 which passes within a cylinder 45 where it terminates in a piston 46. A suitable rigid arm 47 forms a guide bearing for the piston rod 44. The piston 46 is normally maintained at one end of the cylinder 45 by a spring 48 and is arranged to be moved against the spring pressure by fluid pressure admitted by way of pipe 50 to the end of the cylinder 45 on the opposite side of the piston 46 from the spring 48. This pipe 50 communicates with a storage tank 51 containing compressed air or other suitable pressure fluid for the purpose intended.

For controlling the admission of pressure fluid to the cylinder 45, by way of pipe 50, at will from a distance, a multiple port control valve 52 is interposed at a suitable point in the length of the pipe 50 and when in one position establishes communication between the tank 51 and the cylinder 45, but in its normal position causes the cylinder to be connected to the atmosphere and closes the tank portion of the pipe 50. The control valve 52 is, preferably, of the rotary type and is operated by the action of a reciprocal valve 53 through a rack and pinion means 54, all of which is fully described in detail in co-pending application Ser. No. 67,947, patented June 6, 1922, Patent No. 1,418,793, for radio system of dirigible control. In view of this the present description will be limited to an identification of the parts as a repetition is deemed unnecessary. The valve 53 has a stem 55 forming the core of a solenoid 56 which is arranged to be energized by the closing of a circuit 57 including a battery 60, a terminal 61 and an armature switch 62, this latter being normally held by a spring 63 to break the circuit 57. A stationary electro-magnet 64 is located in operative relation to the armature 62 and is arranged to be energized by a closed oscillatory circuit including a conductor 65, a detector 66, condensers 67 and a secondary inductance coil 70, which is inductively con-

nected to a primary inductance coil 71 of an open aerial circuit 72 arranged to respond to radiant energy. Thus when an impulse is received by the aerial circuit 72 the electro-magnet 64 will be energized and thereby close the circuit 57 to cause the solenoid 56 to actuate the valve 53 and admit pressure fluid to shift the ratchet mechanism 54 and position the rotary control valve 52 correctly to cause pressure fluid to pass by way of pipe 50 to the cylinder 45. This action takes place, preferably, through the sending of a long impulse, thus allowing the rotary valve 52 to be adjusted for other operative positions by a short impulse or a succession of short impulses. While the foregoing is described as the preferred construction it should be understood that there are many ways in which the opening and closing of the pipe 50 to fluid pressure may be accomplished and the invention is not limited to the form here described.

In the operation of this form of the invention an impulse of the proper character received with the parts in the position shown in Fig. 1, will cause the pressure fluid to enter the cylinder 45, thereby moving the piston 46 and causing the rack 43 to turn the gear 42 so that the pawl 41 rotates the ratchet 40 through a quarter of a revolution. The spindle 35 is correspondingly turned and the valve 34 thereupon closed. Another impulse is then sent to exhaust the cylinder 45 and restore the parts to normal position, but the valve 34 is left in closed position. To open the valve 34 again to release the smoke to give an indication of the position of the torpedo, an impulse is sent, as above described, and the ratchet 40 is again given a quarter turn thereby opening the valve 34. The valve 34 may thus be controlled in any desired manner, being left open to emit a continuous smoke trail, or intermittently operated to cause a succession of smoke puffs to be emitted.

In the form of the invention shown in Fig. 3, the firebox 12 contains a chemical 73 requiring air to support combustion and give off a dense smoke, and to this end two tubes 74 and 75, leading respectively from different parts of the firebox 12, are provided to establish communication with the exhaust pipe 11 and permit air to circulate through the firebox 12 in contact with the chemical 73. The spindle 35, in this instance, carries two valves 76 and 77, one located in the tube 74 and the other in the tube 75, both being controlled to simultaneously open or close the two passages between the firebox 12 and the exhaust pipe 11. The distant control and the percussion firing means are preferably the same as shown in connection with the form of Fig. 1.

In Fig. 4 another form of the invention is shown wherein the smoke is produced by

the introduction of oil to the turbine from which it passes by way of the exhaust 11 in the form of a dense smoke. In this figure a turbine 80 is shown diagrammatically as 5 connected through suitable gearing 81 with the main shaft 82 and arranged to receive oil for smoke producing purposes by way of a pipe 83.

For supplying and feeding oil to the pipe 10 83, an oil reservoir 84 is provided having an outlet pipe 85 in communication with the suction side of a pump 86, here shown as a pump of the three plunger type, which has its discharge side connected to the feed pipe 15 83 and is arranged to be driven from a suitable shaft 87 in any well known manner.

In order to control the supply of oil to the turbine a by-pass 90 is arranged around the pump 86 to establish communication, 20 under certain conditions, between the suction pipe 85 and the discharge pipe 83, so that all or a portion of the oil may be diverted from the turbine 80. This by-pass 90 contains a control valve 91, preferably 25 of the rotatable plug type, which may be turned from open to closed position and vice versa by the action of a ratchet 92 fixed to a stem 93 extended from the movable valve element, this ratchet 92 being arranged to be 30 turned step by step through the operation of a gear 94 loosely carried by the stem 93 and operating a pawl 95 which engages the said ratchet 92. The gear 94 is operated by the rack 43 and piston 46 construction described in connection with the form shown 35 in Fig. 1, and is under control of the distant operating means as heretofore described. Preferably the ratchet 92 is of the four toothed type so that each stroke of the piston 46 causes the stem 93 and the valve 91 40 to move a quarter of a revolution, and the action is such that the by-pass 90 is alternately opened and closed, but may remain in either condition as desired.

45 For regulating the flow of oil through the by-pass 90 a needle valve 100 may be employed and so adjusted as to throttle the by-passed oil to the desired degree.

In this form of the invention the valve 91 50 is normally in open position so that the oil circulates around the pump 86 and no position-indicating smoke is discharged by way of the exhaust pipe 11. When it is desired to locate the position and course of the torpedo, an impulse is sent to cause the piston 46 to shift the rack 43 and thereby turn the valve 91 to closed position, whereupon the oil is pumped directly to the turbine from 55 which it is discharged by way of the exhaust in the form of smoke, which rises to the surface of the water and is visible to the observer.

60 It will now be apparent that a complete, unitary control system has been devised whereby the position and course of a sub-

merged body may be determined and followed by a distant observer, thereby making it possible to direct that body as desired or return it to a predetermined course in case of deviation.

70 While several forms for accomplishing the desired end are here shown, it is to be understood that they are only by way of example and the scope of the invention is not to be taken as limited in any way, for, obviously the construction is susceptible of modification and change in many particulars without departing from the invention.

Having thus fully described my invention I claim:—

80 1. In a position revealing system, a submerged body, a smoke producing substance carried by said body, means to cause said substance to produce smoke, and means to release said smoke from said body at will.

85 2. In a position revealing system, a submerged body, a smoke producing substance carried by said body, means to cause said substance to produce smoke, and means controlled by radiant energy to release said smoke from said body.

90 3. In a position revealing system, a submerged body, a smoke producing substance carried by said body, means to cause said substance to produce smoke, and means controlled from a distance for releasing said smoke to indicate the position of said body.

95 4. In a position revealing system, a movable body, a smoke producing substance carried by said body, means to cause said substance to produce smoke, and means operable at will from a distance for releasing said smoke to indicate the position or course of said body.

100 105 5. In a position revealing system, a movable body, a smoke producing substance carried by said body, means to cause said substance to produce smoke, and means responsive to radiant energy for releasing said smoke to indicate the position or course of said body.

110 6. In a position revealing system, a torpedo, a fire-box carried thereon, a smoke producing substance in said fire-box, means to automatically ignite said substance at a predetermined time, a discharge conduit from said fire-box to the exterior of said torpedo, and means to open and close said conduit at will, whereby smoke is emitted to indicate the position or course of said torpedo.

115 120 7. In a position revealing system, a torpedo, a fire-box carried thereon, a smoke producing substance in said fire-box, means to automatically ignite said substance at a predetermined time, a discharge conduit from said fire-box to the exterior of said torpedo, and means responsive to radiant energy for opening or closing said conduit, whereby smoke is emitted at will to indicate the position or course of said torpedo.

8. In a position revealing system, a torpedo, a fire-box carried thereon, a smoke producing substance in said fire-box, means operated by the discharge of said torpedo to ignite said substance, a discharge conduit from said fire-box to the exterior of said torpedo, and means to control the discharge of smoke through said conduit, whereby smoke is emitted at will to indicate the position or course of said torpedo.
9. In a position revealing system, a torpedo, a fire-box carried thereon, a smoke producing substance in said fire-box, means operated by the discharge of said torpedo to ignite said substance, a discharge conduit from said fire-box to the exterior of said torpedo, and means responsive to radiant energy to control the discharge of smoke through said conduit, whereby smoke is emitted at will to indicate the position of said torpedo.
10. In a position revealing system, a torpedo, a fire-box carried thereon, a smoke producing substance in said fire-box, means to automatically ignite said substance, a discharge conduit from said fire-box to the exterior of said torpedo, means to admit air to said fire-box, and means to open or close said conduit at will, whereby smoke is emitted to indicate the position of said torpedo.
11. In a position revealing system, a torpedo, a fire-box carried thereon, a smoke producing substance in said fire-box, means to automatically ignite said substance, a discharge conduit from said fire-box to the exterior of said torpedo, means to admit air to said fire-box, and means to simultaneously control said air and said conduit, whereby smoke is emitted to indicate the position of said torpedo.
12. In a position revealing system, a torpedo, a fire-box carried thereon, a smoke producing substance in said fire-box, means to automatically ignite said substance, a discharge conduit from said fire-box to the exterior of said torpedo, means to admit air to said fire-box, and means responsive to radiant energy for simultaneously controlling the admission of air to said fire-box and the discharge of smoke to the exterior of said torpedo.
13. In a position revealing system, a movable body, means carried thereby for producing a visible vapor, and remote control means operable at will to release said vapor.
14. In a position revealing system, a movable body, means carried thereby for producing a visible vapor, and means controlled by radiant energy and operable at will to release said vapor.
15. In a position revealing system, a movable body, means carried thereby and positioned wholly within the body for producing a position indicating instrumentality and means controlled from a remote source, operable at will, for releasing said indicating instrumentality.
16. In a position revealing system, a movable body, means carried thereby and positioned wholly within the body for producing a position indicating instrumentality and means controlled by radiant energy from a remote source, operable at will, for releasing said indicating instrumentality.
17. In a position revealing system, a torpedo, means carried thereby for producing a visible vapor and means controlled from a remote source by radiant energy and operable at will for releasing said vapor in a continuous stream or in intermittent puffs, as desired.
18. In a position revealing system, a movable body, means carried thereby for producing a visible vapor and means controlled from a remote source by radiant energy and operable at will for releasing said vapor in a continuous stream or in intermittent puffs, as desired.
19. In a position revealing system, a movable body, means carried thereby and positioned wholly within the body for creating a position indicating instrumentality and means operable at will from a remote source for controlling the emission of said instrumentality from the body.
20. In a position revealing system, a movable body, means carried thereby for creating a visible vapor and means operable at will from a remote source for controlling the emission of said visible vapor from the body.
21. In a position revealing system, a submersible body, means carried thereby and positioned wholly within the body for creating a position indicating instrumentality and means operable at will from a remote source for controlling the emission of said instrumentality from the body.

Signed at New York, in the county of New York and State of New York, this 1st day of April A. D. 1919.

JOHN HAYS HAMMOND, JR.
